JEWELRY CHARM OR SIMILAR ARTICLE

Roy A. Burkhart and Louise B. Freeland, Columbus, Ohio

Application July 26, 1955, Serial No. 37,123

Term of patent 14 years

(Cl. D45—17)

FIG. 1.

FIG. 2.

FIG. 3.

FIG. 4.

Fig. 1 is a front elevational view of a jewelry charm showing our new design;

Fig. 2 is a rear side elevational view;

Fig. 3 is a transverse sectional view taken along the line 3-3 of Fig. 1; and

Fig. 4 is an edge elevational view thereof.

The dominant features of our design reside in those portions shown in full lines on the drawing.

We claim:

The ornamental design for a jewelry charm or similar article, substantially as shown and described.
